UNITED STATES PATENT OFFICE.

WILHELM HILDEBRAND, OF BERLIN, GERMANY, ASSIGNOR TO KNORR-BREMSE AKTIENGESELLSCHAFT, OF LICHTENBERG, BERLIN, GERMANY.

BRAKE APPARATUS FOR RAILWAY VEHICLES.

1,424,303.

Specification of Letters Patent. Patented Aug. 1, 1922.

Application filed July 21, 1920. Serial No. 393,038.

To all whom it may concern:

Be it known that I, WILHELM HILDEBRAND, a citizen of the German Republic, residing at Neue Bahnhofstrasse 9-17, Lichtenberg, Berlin, O. 112, Germany, have invented certain new and useful Improvements in Brake Apparatus for Railway Vehicles (for which the following patents have been granted to me: in Germany, 306,686, dated December 23, 1916; Hungary, 72,310, dated February 20, 1917; Switzerland, 75,611, dated February 19, 1917; Spain, 63,995, dated March 1, 1917; Denmark, 23,999, dated February 18, 1918; Turkey, 15 2,813, dated March 26, 1918; Norway, 13,701, dated January 23, 1918; and for which I have filed applications in Austria, 772/17, dated Feb. 17, 1917; Sweden, 598/17, dated February 28, 1917; Italy, 240/244, dated 20 March 15, 1917; Great Britain, 3,666, dated March 13, 1917; Holland, 9,454, dated February 19, 1918; Finland, dated June 21, 1919), of which the following is a specification.

25 This invention relates to a double chambered brake in which a pressure equalizing communication exists between the working chamber and the idle chamber of the brake cylinder in the released position of the 30 brake-cylinder piston.

Known contrivances of this type have the disadvantage that when the brake actions are initiated or air is allowed to escape from the idle chamber of the double chambered 35 brake cylinder, the communication between the working chamber and the idle chamber through the pressure-equalizer is still open, so that compressed air can still escape from the working chamber into the idle chamber, 40 and the brake-cylinder piston, particularly under some circumstances, is either not displaced or remains in the released position. At the same time the pressure valves in the working chamber are thereby adversely affected, as a loss of air occurs therein owing 45 to the escape of compressed air. By diminishing the open cross sectional area of the pressure-equalizing communication these disadvantages can of course be reduced, but 50 not absolutely removed; moreover by the narrowing of the pressure equalizing communication the quick filling up of the working chamber, desired for instance in vehicles that may subsequently be attached to the 55 train, is adversely affected.

According to this invention the disadvantages above set forth are practically obviated by arranging for the pressure equalizing communication to be regulated by the control valve which governs the outlet of compressed air from the idle space. This adjustment is effected in such manner that the controlling slide-valve shuts off the pressure-equalizing communication in the control valve before it opens the outlet from the idle 60 chamber to the atmosphere.

The drawing shows a diagrammatical representation of the subject-matter of the invention.

The double chambered brake-cylinder *a* 70 is divided by the brake piston *b*, into two spaces *B*, *A*, that is, the idle space and the working chamber. The piston rod *c* of the brake piston is attached to the brake gear through the closure piston *d*. The idle 75 chamber *B* communicates, in the released position of the brake piston as illustrated, through passages, pipes or the like, *e*, *f*, one at each end, with the slide-valve grating or grid *m* of the control valve *g*, while a pipe *h* for the compressed fluid leads from the working chamber to the controlling slide-valve chamber *C* of the control valve *g*. The controlling piston chamber *i* communicates with a branch pipe *k* with the main brake 85 pipe *l*, and can communicate by a pipe *q* with a passage *s* in the valve *m*, which passage *s* in the position shown makes communication with the pipe *e* as shown in dotted lines in the drawing. In the normal 90 or released position of the control piston *n* as illustrated, the control slide valve *m* closes the opening of the pipe *e* to the atmosphere through *p* in the slide-valve grating, while the passage *f* is in this position open to the 95 controlling slide-valve chamber *C*, so that the working chamber *A* can be filled with compressed air from the brake pipe, through the controlling slide valve *m*, along the path *k*, *i*, *q*, *m*, *e*, *B*, *f*, *C*, *h*. When the control piston moves from the normal position into the right-hand end position, not specifically illustrated, the controlling slide valve *m*, which is carried along by the controlling piston *n*, first covers the opening of the passage *f* in the slide-valve grating, so that the pressure equalizing communication *B*, *f*, *C*, *h* *A* from the idle chamber to the working chamber is interrupted, the passage *e* in the slide-valve grating being then uncovered 105 110.

and at the same time connected through the space o of the D-slide valve with the opening p leading to the atmosphere. Consequently compressed air escapes from the idle chamber B along the path e, o, p to the atmosphere, and the brake piston b is displaced from the released position towards the left into the braking position, which is not specifically illustrated. As the pressure outlet from the idle chamber B is not opened until after the pressure equalizing communication between the working and idle chambers is interrupted, the brake piston b is prevented from remaining still when the brake actions are initiated, the said brake piston being displaced with certainty, and consequently the brake gear is tightened, and the escape of compressed air from the working chamber, or a loss of pressure therein, thereby effectually prevented.

The invention is of course not limited to the special construction of the double chambered brake described above and illustrated, especially as the drawing merely gives a diagrammatical arrangement of the subject-matter of the invention. Therefore the most manifold modifications and constructional forms may also be employed, without departing from the nature of the invention. For instance the internal cross-sectional area of the passages e, f, h are determined according to the purpose and application; the control valve g may further be directly applied to the brake cylinder. The invention may also be applied to a combination brake consisting of a double chambered brake and a single chambered brake in combination with a corresponding control valve.

What I claim and desire to secure by Letters Patent of the United States is:—

1. In double chambered brake apparatus

for railway vehicles, a brake cylinder of uniform working diameter, a piston movable therein dividing said cylinder into a working chamber and an idle chamber, a valve chamber, a valve movable in the said valve chamber, pressure equalizing communications on both sides of the piston opening into the said valve chamber, and an outlet to atmosphere from the brake cylinder in front of the said piston, the said valve controlling the said pressure equalizing communication and also the said outlet.

2. In double chambered brake apparatus for railway vehicles, a brake cylinder of uniform working diameter, a piston movable therein dividing said cylinder into a working chamber and an idle chamber, a valve chamber, a valve movable in the said valve chamber, pressure equalizing communications on either side of the piston opening into the said valve chamber, and an outlet to atmosphere from the brake cylinder in front of the said piston, so positioned that in the movement of the said valve one of the said equalizing communications is closed before the said outlet is opened.

3. In double chambered brake apparatus for railway vehicles, a twin chambered brake with only one brake cylinder, a piston movable in the said cylinder and dividing same into a working chamber and an idle chamber, a valve chamber, a free constant communication from said working chamber to said valve chamber, communications from each end of said idle chamber to said valve chamber, and an outlet to atmosphere from said valve chamber and a valve movable in said valve chamber, the said valve controlling the said outlet and the said communications from said idle chamber.

WILHELM HILDEBRAND.
